US00D405430S

United States Patent [19]

Matsushima

[11] Patent Number: Des. 405,430

[45] Date of Patent: **Feb. 9, 1999

[54] **INNER TUBE FOR USE IN A SEMICONDUCTOR WAFER HEAT PROCESSING APPARATUS**

5,314,574 5/1994 Takahashi ..... 414/935 X
5,320,218 6/1994 Yamashita et al. ..... 414/935 X

[75] Inventor: **Noriaki Matsushima**, Kanagawa, Japan

Primary Examiner—Brian N. Vinson
Attorney, Agent, or Firm—Ladas & Parry

[73] Assignee: **Tokyo Electron Limited**, Tokyo-To, Japan

[57] CLAIM

[**] Term: **14 Years**

I claim the ornamental design for inner tube for use in a semiconductor wafer heat processing apparatus, as shown and described.

[21] Appl. No.: **74,301**

DESCRIPTION

[22] Filed: **Jul. 24, 1997**

FIG. 1: a perspective view of a inner tube for use in a semiconductor wafer heat processing apparatus;

[30] **Foreign Application Priority Data**

FIG. 2: a front elevational view thereof, the rear elevational view, the right side view and the left side view are identical with the front view;

Jan. 31, 1997 [JP] Japan 9-2653

FIG. 3: a top plan view thereof;

[51] **LOC (6) Cl.** **13-03**

FIG. 4: a bottom plan view thereof; and,

[52] **U.S. Cl.** **D13/182**

FIG. 5: a cross sectional view thereof taken along line V-V in FIG. 3.

[58] **Field of Search** D13/182; D15/144, D15/144.1, 199; 414/935-941, 217, 147; 437/247, 546; D23/259, 262, 266
